UNITED STATES PATENT OFFICE.

LOUIS A. CASGRAIN, OF BEVERLY, MASSACHUSETTS, ASSIGNOR TO UNITED SHOE MACHINERY COMPANY, OF PATERSON, NEW JERSEY, A CORPORATION OF NEW JERSEY.

MACHINE FOR INSERTING FASTENINGS.

1,048,134.

Specification of Letters Patent.

Patented Dec. 24, 1912.

Application filed March 17, 1906. Serial No. 306,612.

To all whom it may concern:

Be it known that I, Louis A. CASGRAIN, a citizen of the United States, residing at Beverly, in the county of Essex and Commonwealth of Massachusetts, have invented 5 certain Improvements in Machines for Inserting Fastenings, of which the following description, in connection with the accompanying drawings, is a specification, like 10 reference characters on the drawings indicating like parts in the several figures.

This invention relates to machines for inserting fastenings and is herein shown as embodied in a machine of the type represented by Letters Patent of the United States, No. 669,023, granted February 26, 1901, and No. 693,686, granted February 18, 1902. Each of the machines shown in said Letters Patent forms from continuous wire 20 a fastening having a shank with a clenching point and having a depending head shorter than the shank and then inserts this fastening into the stock, turning back, or clenching, the point of the shank. The machine 25 of Letters Patent No. 693,686 also forms an opening or cut in the stock to receive the head of the fastening and, after the fastening has been inserted, closes the stock over it. However, while the various features of 30 the present invention may conveniently be, and preferably are, embodied in machines of the character described and claimed in the said patents, yet some of these features are generally applicable to machines for inserting 35 fastenings of any kind commonly employed to secure together layers of material or to attach the soles of boots and shoes.

A principal feature of the present invention consists in means for forming in the 40 work or stock an opening for the head of the fastening, in combination with means for forming another opening for the shank of the fastening. The opening for the shank insures that the fastening will be guided 45 accurately and with certainty in its passage into the work, so that it shall be driven straight and so that when a sole is being attached to a lasted shoe, practically all liability of the point of the shank running 50 out of the upper is eliminated. This and other features of the invention may be embodied in any machine for inserting fastenings which have a head and a shank and is not limited to a machine which is adapted

to insert a fastening of the specific character described in the patents above mentioned. In the preferred embodiment of this feature of the invention the opening for the head of the fastening is made by a device which forms a comparatively shallow recess in the 60 surface of the work extending in the direction in which the work is fed, while the opening for the shank is made by a device, such as an awl, which enters the work through this recess. It will be obvious, 65 therefore, that the opening for the head and the opening for the shank intersect so that they, together, constitute a continuous opening which forms a seat or pocket to receive the fastening. Hence, broadly stated, the 70 invention comprises, in one aspect, a plurality of separately actuated devices for forming in the stock an opening or seat for the fastening. Preferably, also, means is provided for closing the stock over the inserted 75 fastening. As hereinafter described, the device for forming the opening for the head may be constructed to cut a slit in the surface of the work and to spread the stock at the sides of this slit so as to widen it. After 80 the fastening has been inserted, the closing device presses the stock together over the fastening, thus closing the opening. It will be understood that in this aspect of the invention it includes a machine which has 85 means for forming an opening for the shank of a fastening, means for inserting a fastening, and means for closing the stock over the fastening whether or not the opening in the work for the head of the fastening is 90 made by this same machine or by some other machine or by hand.

Another feature of the present invention relates to the mechanism for actuating the awl. It is desirable to have the awl pass 95 substantially or nearly through the stock whatever the thickness of the work. Since the upper side of the work, through which the awl enters, is always at the same height whether the work be thick or thin, the awl 100 must descend a distance which will vary according to the thickness of the work if it is to penetrate to the same point relative to the lower side of the work for all thicknesses. In order to obtain this desirable result, in the present machine the awl bar, in which preferably the awl is positively 105 locked, is connected to a lever which in turn

has connections to the horn or work-support upon which the work is sustained. This lever is provided with a stud adapted directly to engage a cam which actuates the awl bar to cause the awl to enter or penetrate the work. Thus, the lever may be oscillated independently either about its connection to the work-support or about its stud as a fulcrum. The connections between the awl and the work-support are so proportioned that the awl is moved in the same direction and for the same distance as the work-support when the latter rises or falls to accommodate various thicknesses of work. Hence, when the awl is actuated by its cam, the lower limit of its stroke is always at a predetermined distance from the lower side of the work sustained on the work-support. Preferably, also, the connections between the awl and the work-support are provided with adjusting means whereby this distance may be regulated, if desired.

In machines for inserting fastenings, it is common to provide a driver bar, having a driver, with a strong spring or springs for imparting to the driver bar its operative stroke, the bar coming into engagement with a stop that limits its stroke. Usually this bar is raised positively by a lug which directly engages the bar or by a cam which actuates the bar through a lever. That portion of the stop which contacts with the bar is generally slightly yielding, being made of leather or like cushioning material, and therefore after its operative stroke, the driver bar rebounds a substantial distance from the stop. Heretofore, so far as I am aware, no attempt has been made to take advantage of the force of this rebound in retracting or raising the driver bar to its normal or highest position. Hence, the lifting cam, in some instances, has been so designed that it commences to raise the bar during the downward movement which follows a rebound, resulting in a sharp blow to the bar and its actuating mechanism. In such case, this mechanism has to resist and overcome not only the weight of the moving parts and the force of the spring or springs, referred to, but also the kinetic energy due to the motion of these parts. Consequently, an unnecessary strain is put upon the machine and, also, the cam-actuated lever for raising the bar frequently is broken, where such a lever is employed. Accordingly, another object of the present invention, broadly stated, is to utilize, for the raising of a driver bar, the force with which it rebounds from the work or from the stop which it strikes at the termination of its driving stroke. To this end, the cam or other means for raising the bar is so designed that it picks up, or acts to raise, the bar just as it rebounds from the work. Hence, the force of rebound does not have to be overcome, but

it actually assists in raising the bar to its normal position.

The leather or like material which acts as a stop for the driver bar gradually wears away, and hence, unless provision is made against it, the lower limit of the stroke of the bar descends so that the spring or springs which actuate the driver bar will cause a greater force to be exerted upon the fastening being driven. Furthermore, there is a liability that, as the lower limit of the stroke of the bar descends, the cam-engaging projection or stud moving with the driver bar under the influence of its actuating spring or springs will strike the lifting cam, near the end of the driving stroke, before the bar comes into engagement with its stop, unless considerable clearance has been given to the corresponding portion of the cam.

One of the features of the machine of the present invention is the provision of means for maintaining the stroke of the driver substantially constant by the adjustment of the position of the stop itself, as a result of which the disadvantages above specified are obviated. Preferably, the stop comprises a cup, containing a cushioning material, such as leather washers or the like, the cup being adjustable longitudinally of the driver bar.

A further important feature of the present invention relates to the means for feeding the wire from which the fastenings are made. In its broader aspect, this feature comprises means for varying automatically the length of wire fed to the fastening-forming mechanism by changing the rate of feed without changing substantially the points in the cycles of operation at which the feeding of the wire begins and ends. In the preferred form of wire-feeding mechanism, the length of wire fed is measured accurately according to the thickness of the work at the point at which the fastening is to be inserted, and the mechanism which regulates the feed of the wire acts positively, with certainty, and with no "lost motion" during the feeding movement, so that the time occupied by this movement is always the same relatively to the time occupied by the whole cycle of operations of the machine, but the rate of feed is accelerated or retarded according to the thickness of the work. In the machine about to be described, the length of wire fed may be regulated automatically by the adjustment of the position of a connecting pin toward and from the axis of an arm or crank, thus varying the stroke of the wire-engaging device which is connected to the pin and which is operated by the oscillation of the arm. The pin is preferably mounted on a block movable in a slot in the arm and the position of the block in the slot is varied automatically ac-

cording to the position of the work-support and, therefore, according to the thickness of the work calipered by the work-support. In order to avoid any liability of feeding 5 wire by a movement of the work-support when the machine is at rest, the mechanism for actuating the arm or crank is so timed that the slot is left in substantially a vertical position when the machine stops so that the 10 wire-feeding mechanism will not be actuated by the vertical movement of the block and of the work-support. Furthermore, the feeding mechanism includes a friction clutch by which an accurate and reliable 15 operation of the feeding mechanism is obtained and by which the mechanism is rendered compact and comparatively noiseless. While the present machine embodies most 20 of the features of the earlier machines above mentioned, the new combinations of parts have made necessary a complete reorganization of said earlier machines. Furthermore, the present invention comprises, in addition to the novel features already specifically 25 mentioned, various arrangements and combinations of parts and certain details of construction which will be hereinafter described and claimed.

Referring now to the drawings:—Figure 30 1 is a view in side elevation of a machine which embodies my invention in its preferred form, the parts being shown in the positions they occupy when the machine is at rest; Fig. 2 is a view in front elevation of 35 the upper portion of the machine; Fig. 3 is a corresponding view in rear elevation; Fig. 4 is a view of the head of the machine similar to Fig. 1, but with the parts in the positions they occupy just before the fastening 40 is to be driven and with the frame partially cut away, various parts, particularly those beyond the central transverse plane of the machine, being omitted; Fig. 5 is a view in sectional elevation taken substantially upon 45 the central transverse plane of the machine; Fig. 6 is a plan view with certain parts shown in section of the work gage and work-feeding mechanism; Fig. 7 is a detail view in perspective of a portion of the mechanism 50 shown in Fig. 6; Fig. 8 is a perspective view of a portion of the device for feeding the wire, some of the parts being cut away; Fig. 55 9 is a detail view in front elevation of a portion of the device shown in Fig. 8 with the frame in section; Fig. 10 is a sectional plan view upon the line 10—10 of Fig. 9; Fig. 11 is a perspective view of a portion of the mechanism for forming the fastenings, as seen obliquely from the rear; Figs. 12 to 14, 60 inclusive, are detail views of the same mechanism in different positions; Fig. 15 is a view, partly in elevation and partly in section, showing the work clamped between the work-support and the presser-foot, together 65 with other related parts; Figs. 16 and 17, re-

spectively, are detail views of the cutting device and of the closing device; Fig. 18 is a perspective view of a piece of stock showing two fastenings inserted into the cuts or openings made for their heads in the surface 70 of the stock, one of the cuts being shown open and the other closed.

In the form of the invention illustrated in the drawings, 2 represents the frame for supporting the various parts of the machine. The driving pulley 3, constituting the loose member of a clutch, may be connected to and disconnected from the other member 4, which is fixed to the main shaft 5, by mechanism similar to that fully shown and described in the prior patents, above mentioned, and comprising a spring 6 normally tending to force the loose member 3, which is carried upon a sliding sleeve (not shown), into operative engagement with the fixed 80 member 4. In the prior construction, a pin was mounted to slide in the fixed member so as to bear against a flange on the sleeve and, when the operator desired to release the clutch, he brought the inclined end of a curved arm pivoted on the frame into operative relation with the end of the slidale pin which, as it traveled along the incline, was moved longitudinally to release the clutch 85 members.

With the present improved construction, the flanged sleeve is acted upon by two or more pins 7 slideable in the fixed clutch member 4 and secured to a segmental curved bar or plate 8 having an inclined or tapered end 9. A pin 10, slideable in a bracket of the machine frame, may be forced outwardly so that the inclined end 9 of rotating bar 8 will engage it, thus pushing bar 8 outwardly along the shaft in opposition to spring 6 to 105 release the clutch members to cause the machine to stop. When pin 10 is released so that it may move inwardly, spring 6 will force the clutch members into engagement to start the machine. A finger 11, having an inclined face to engage pin 10, is secured in an arm 12 fixed upon a rock shaft 13 which is suitably supported in bearings in the machine frame. Fixed to this shaft 13 is an arm 14 connected to a rod 15 which extends downwardly to a treadle 16 pivotally mounted upon a bracket 17 at the base of the machine. A spring 18 secured at one end to arm 14 and at the other to a fixed projection 19 maintains the treadle normally raised 110 and the clutch members disengaged. A stop 20, having provision for adjustment, if desired, engages arm 12 to limit the movement, under the influence of spring 18, of the mechanism just described.

Upon the main shaft 5 are two cam blocks 21, 21^a having slightly bulging or eccentric portions adapted to be engaged by coöperating brake shoes 22 so as to stop the machine, when desired, at a definite point in 115 120 125 130

the cycle of operations. The brake shoes are supported on the shaft 13 which is provided with grooves 23 to receive complementary projections or lugs 24 on the brake shoes, the arrangement being such that these shoes are thrown into and out of operative position relative to blocks 21, 21^a when the treadle 16 is moved to actuate the clutch. This feature of construction is the same in principle as in my prior patents and need not be further described in detail. As shown, each brake shoe is held to the shaft 13 by a bent U-shaped spring 25 which straddles the shoe. The ends of the spring are connected to pins 26 on each side of the shoe and the intermediate loop is bent into a recess or slot in the shaft, as shown in Figs. 4 and 5, so that each shoe is held against lateral movement on the shaft, and so that the shoes will be drawn away from the blocks 21 and 21^a more certainly as the shaft 13 is rotated to start the machine. As shown in Figs. 4 and 5, the brake shoes may be slotted at 27 and a tapered pin or wedge 28 may be driven into a hole in the side of each shoe so as to widen said slot and force the braking surface of the shoe toward the block 21 or 21^a to compensate for wear.

The work into which fastenings are to be inserted is clamped between a fixed presser foot, hereinafter to be described, and a vertically movable work-support or horn 30, mounted in an arm 31 to rotate upon the horn spindle 32. A long sleeve 33 rigid with a cap or plate 34 constitutes a bearing or guide for the spindle 32, the sleeve being slotted at its lower end to receive a bar 35 extending from the spindle into the slots to prevent rotation of the spindle.

The main frame 2 has a boss 36 with a horizontal bearing surface upon which the plate 34 may be swung about a pivot 37 in order to carry the work-support out of vertical alignment with the presser-foot so as to render the parts above the work-support readily accessible. The plate 34 is provided with a notch through which a stud 38 projecting upwardly from boss 36 passes when the plate is swung laterally to bring the work-support into position. A handle 39 with an eye having screw threads to engage the threads of stud 38 serves to clamp the plate 34 to the boss 36 so as to prevent lateral movement of the work-support during the operation of the machine. An adjusting screw 40 in plate 34 bearing against stud 38 regulates the lateral adjustment of the work-support when in working position.

The mechanism for actuating the work-support, while particularly useful in a machine having the features herein claimed, is also capable of use in other relations and is not, therefore, herein specifically claimed, it having been made the subject-matter of another application filed by this applicant

May 21, 1907, Serial No. 374,853. Since, however, some form of actuating mechanism for the work-support will ordinarily be employed in the machine and since some of the combinations herein claimed include to a greater or less extent the mechanism for actuating the work-support, it will now be briefly described.

The spindle 32 is notched at 45 to receive the end of a lever 46, pivoted at 47 in the frame 2. The rear end of lever 46 is connected by a link 48 to a pivot pin 49 mounted in two offset ears 50 at the lower end of a slide 51 which is vertically movable in ways in the machine frame being retained in place by plates 52. A block 53, through which pin 49 passes, has a threaded socket into which is screwed a rod 54. Loosely mounted on the upper end of this rod is a flanged sleeve 56 which is supported upon a coiled spring 57 surrounding the rod and bearing at its lower end upon the upper of two nuts 55. One arm 58 of a two-armed lever, mounted to oscillate on the concentric portion of an adjustable shaft 59 secured in the machine frame, is provided with a hole 60 through which the upper ends of rod 54 and of sleeve 56 pass, the flange of the sleeve engaging the lower recessed side of the arm. The other arm 61 of the two-armed lever has a stud or roll 62 running in a cam track 63 in the right side of cam block 21^a, as viewed in Fig. 3.

In the rear of the hole 60 in arm 58 is a transverse pin 64 supporting two pawls 65 which are adapted to engage corresponding ratchet teeth 66 on the slide 51. A leaf spring 67 supported by a lug 68 at the end of the arm 58 forces the pawls toward their ratchet teeth. An adjustable plate 69, having the function of a shield, rests over a greater or less number of the ratchet teeth for a purpose to be described, being clamped in adjusted position under retaining plates 52. A spring 70 connected at its upper end to projection 19 and at its lower end to an adjustable collar 71 on rod 48 counterbalances, to a greater or less extent, the work-support 30 and its connected parts. Preferably, the strength of the spring and the adjustment of collar 71 are such that the work-support constantly tends to move to its lowest position.

During each cycle of operations, the arm 58, actuated by cam groove 63, first raises the work-support through spring 57 to clamp the work with a yielding pressure. When, or just before, arm 58 reaches the lower end of its stroke, pawls 65 engage the ratchet teeth 66, thus providing a positive connection between the work-support and its actuating cam so that the work-support is locked rigidly in raised position. Preferably the shield 69 is so adjusted that the pawls engage the ratchet teeth just be-

fore arm 58 completes its downward stroke so that the final movement of the arm causes the work-support to be raised positively a short distance to compress the work, after 5 which it is locked, as described. The extent of the compressing or lifting movement of the work-support depends upon the position of the shield 69 and is independent of the thickness of the work. The force exerted through spring 57 may be varied by 10 adjusting nuts 55 on rod 54 with or without adjusting rod 54 in the socket in block 53.

After the work has been clamped by the work-support, an opening, recess, or indentation is cut or otherwise made in the upper surface of the work to receive the head of a fastening and another opening or hole is made to extend into the work from said recess to receive the shank of the fastening, 15 as already stated. The opening for the head of the fastening is preferably made by a cutting device 75 (see Fig. 16) similar to that shown and described in prior Patent No. 693,686, which device displaces the stock by raising it on each side of the opening, 20 as indicated at *m*, Fig. 18, so that the fastening may be inserted. The cutter 75 is secured in a swinging carrier 76 pivoted at 77 to the head of the frame 2. A toothed segment 78 on this carrier meshes 25 with the teeth 79 on the side of a vertically guided rack 80, shown in Fig. 2, which also has teeth 81 on its rear side meshing with the teeth 82 of a forwardly extending arm 83 secured to a short rockshaft 84 mounted in one side of the frame 2. An arm 85, also secured to this rockshaft, is provided with a roll or stud 86 which runs in a cam track or 30 groove 87 formed on the inside of a cam wheel 88 on the main shaft 5.

A closing device, shown as a finger 89, (see Figs. 15 and 17), similar to that disclosed in Letters Patent No. 693,686, is also pivoted on carrier 76, being maintained in 45 position by a spring 90 which bears upon a flat surface of a block 91 integral with the hub of the finger and which is secured at one end to one of the blocks or bars, to be hereinafter described, for clamping the wire 50 while a fastening is being formed. After the fastening has been inserted the finger 89 presses down the stock raised by the cutter 75. This finger is also actuated from cam 88 by the mechanism just described, 55 both the finger 89 and the cutting device 75 being guided by a groove or slot 92 in the presser-foot 93 which is secured rigidly to the fixed clamping block just mentioned. This presser-foot is similar in construction 60 and function to that shown and described in Letters Patent No. 693,686, but it is provided with an additional transverse opening or slot 94 for the passage of an awl, as will now be described.

65 In order to insure that the shank of the

fastening shall be driven straight into the work, the present machine is provided with means for forming in the work an opening or hole to guide the shank. For this purpose, an awl 100 to reciprocate into and out of the work is mounted in a swinging head or carrier 101 which is clamped upon the eccentric central portion of a pivot shaft 102 oscillating in bearings in the head of frame 2. The awl has a reduced or shoulder portion 103 which fits into a corresponding recess in the awl bar 104 so that it may be positively locked to prevent slipping. The awl bar slides in a guideway in the swinging head 101, being retained in place by a plate 105, which has an extension foot 106 to guide the awl 100, and by lugs 107 projecting laterally from the bar and bearing upon a plane surface 108 of the machine head. 70

Pivoted to the awl bar is a block 109 extending into a slot 110 at the end of an actuating lever 111 which swings on the eccentric central portion of a pivot pin 112 extending through suitable ears or bearings 113 at the upper end of the slide 51 which is connected to the work-support 30, as already described. A stud or roll 114 carried by lever 111 enters a cam track 115 in the left side of cam block 21^a as viewed from the rear of the machine. It will be noted that this lever 111 may be oscillated about either or both of two movable fulcrua 112 and 114. When the block 109 is in its inner position with the awl 100 in approximate alinement with the tip of the horn 30, the fulcrum 114 of lever 111 is at substantially the same proportionate distance from its pivot 112 and from its point of connection to the awl bar 104 as is fulcrum 47 of lever 46 from its points of connection to the horn spindle 32 and to the rod 48. The relative positions of the awl and work-support may be adjusted by turning the eccentric pivot 112. When the work-support moves up or down, the lever 111 is 80 oscillated about stud 114 as a fulcrum so that the awl is moved the same distance and in the same direction as the work-support. Hence, the lower limit of the stroke of the awl is at a predetermined distance from the tip of the horn or work-support, although the work-support in its highest position is at a distance from the fixed presser-foot 93, which varies according to the thickness of the work. If, for example, the pivot 112 is 85 so adjusted that, when lever 111 is oscillated by cam track 115 about pivot 112 as a fulcrum, the awl just reaches the lower side of work of a certain thickness upon the work-support, then if the work of any other thickness is put upon the work-support, the lower limit of the stroke of the awl will be automatically varied, so that still the awl will just reach the lower side of the work. 90

95 The wire *w* from which the fastenings are 100

made is conveniently led from a reel 125 and entered between two feed disks 126, 127, preferably geared together. The periphery of one or both of these disks is grooved as shown in order to guide the wire more accurately and, preferably, the groove is scored or roughened so that the wire will be held more positively. As in Letters Patent No. 693,686, above mentioned, the disk 127 rotates on a pin 128 eccentrically secured to the split stud 129 which is supported in the head of the machine frame. The disk 127 may be moved to and from operative relation with the disk 126 to clamp or to release the wire by means of a handle 130 and, when in operative position, the disk 127 is maintained in engagement with the wire by spring-pressed plunger 131. This mechanism by which a substantially constant pressure is exerted on the wire is essentially the same as that fully described in the said prior patents.

The disk 126 and its gear are fixed on the lower end of a supporting stud 132 to the upper end of which is secured a disk 133 constituting the driven member of a roll clutch. This disk has recesses in its periphery and is surrounded by a clutch-ring 134 so as to form tapering or wedge-shaped spaces 135 between the inner sides of the recesses and the inner wall of the clutch-ring 134. A roll 136 in each space 135 is acted upon by a spring 137 which tends to force the roll into the narrower end of the space. Hence, rotation imparted to clutch-ring 134 in the direction indicated by the arrow in Fig. 8 will cause the rolls 136 to lock the ring and disk 133 together so that the wire will be fed forward. Rotation of the ring in the opposite direction will tend to carry the rolls to the wider ends of spaces 135 and, by reason of the friction and inertia of the parts, the wire engaging disks will remain stationary. However, if desired any suitable checking device may be employed to prevent backward rotation of the disks. It is, of course, obvious that the usual pawl and ratchet connection may be employed instead of this roll clutch, although the latter is preferred since it eliminates the noise and the lost motion which are inherent disadvantages of the pawl and ratchet construction. In such case, however, the interposed shield or shields of the prior patents, above mentioned, are not required.

The clutch-ring 134 has, upon a portion of its periphery, gear teeth 138 meshing with the teeth 139 of a reciprocating rod or rack 140 which slides in a bearing in the head of the machine frame. A connecting rod 141 jointed at 142 to the rod 140 is bored to receive a pin 143 fixed in a block 144, which slides in a slotted arm or crank 145 of a short shaft 146 suitably supported in a bearing in one side of the frame. At its outer end, this

shaft has teeth 147, cut in a portion of its circumference, which intermesh with teeth 148 on the end of a lever 149, loosely pivoted on the treadle-operated shaft 13. This lever is provided at its upper end with a cam stud 70 or roll 150 which runs in the cam track or groove 151 on the inside of fixed clutch member 4 on the main shaft.

The length of wire fed may be regulated by the adjustment of the block 144 in the slotted arm 145. In the machine, herein described, this adjustment is made automatically according to the thickness of the work upon the work-support by connections now to be described. The connecting rod 141 is extended beyond the pin 143 through a slotted block 152 which is carried by a pin 153 eccentrically supported in a sleeve 154 rotatable in a bearing at the upper end of the slide 51. To adjust the normal position 80 of block 144 in the slotted arm 145, sleeve 154 may be rotated by the operator and then clamped in adjusted position by set screw 155. With the construction described, it is evident that the thicker the work, the lower 90 will be the position of the work-support when the work is clamped between it and the presser-foot and the higher will be the block 144 in the arm 145, which results in an increase in the effective length of the crank 95 and hence the stroke of the rod 140 will be increased to feed a greater length of wire corresponding to the increased thickness of the work.

The cam track 151 is given such a shape 100 that the slot in arm 145 will be approximately vertical when the machine comes to rest, which occurs at a definite point in its cycle of operations, as above explained. Any vertical movement of the work-support and, consequently, of the slide 51 when the machine is at rest, will not, therefore, substantially affect the wire-feeding mechanism.

As shown in Fig. 5, the shaft 146 has 110 clamped to it a dog 156 which is adapted to come in contact with an adjustable stop 157 screwed into the frame and locked in adjusted position by any suitable means. Preferably, the head of the stop is provided with 115 a face of leather or the like, to yield slightly as the dog 156 engages it. This device is for the purpose of preventing over-throwing of the wire-feeding mechanism and for insuring that, for a particular position of 120 block 144 in slotted arm 145, the length of successive fastenings severed from the wire will be constant.

The former and the parts which coöperate with it to form a fastening of the character 125 described are, in principle, substantially like the corresponding devices in Letters Patent No. 693,686 and, therefore, will be only briefly described. The wire is fed by disks 126 and 127 into and through a guide-way 130

or groove formed in one or both of two blocks or bars 160, 161. One of these blocks, 160, is adapted to be moved at one end toward and from the other block to clamp the wire while a suitable length to form a fastening is being severed from it. The block 161 is provided with a fixed cutting edge 162 and the anvil 163, and in other respects these blocks are or may be the same as in the prior 10 patented construction referred to. The former 170, comprising the shaper 171 and the bender 172, has been somewhat modified in the present machine. As shown in Fig. 11, a web of material, extending for the full 15 length of the bender, connects it to the shaper and to the body of the former and closes the front side of the driver passage 173 in which the formed fastening is held and from which it is driven, this improved construction 20 forming a guideway in which the fastening is more certainly retained and making the former stronger and stiffer. The guiding plate opposite the end of the anvil which was employed in the prior constructions to close the front side of the driver passage is no longer required, being 25 replaced by the web of the former.

The former is secured to a former bar 174 which slides in a guideway in the side of the 30 swinging head 101 opposite to that in which awl bar 104 slides. A block 175, pivoted to the former bar, extends into a slot 176 at the end of an actuating lever 177 which may be clamped to an eccentric portion 178 of 35 a sleeve 179 loosely supported in a bearing in the frame 2 and through which shaft 13 passes loosely. The sleeve may be adjusted rotatively so as to vary vertically the location of the former when in its highest position and therefore also to vary the curvature 40 of the shank of the fastening, as was done by a somewhat different construction in the prior patents above mentioned. The stud or roll 180 on lever 177 engages the cam track 181 on the left side of cam block 21, as appears in Fig. 3, the shape of the cam track being such as will give the former the desired vertical movements for forming the fastening. Also mounted for reciprocation 45 in the swinging head 101 is the driver bar 190 which has a socket at its lower end to receive a split sleeve 191 into which the end of a driver 192 is inserted. A short screw 193 threaded into the lower end of 50 the driver bar bears against the sleeve 191 and may be screwed up to clamp both the sleeve and the driver in the socket of the driver bar. A long bushing 194 fixed in the swinging head or carrier 101 constitutes a bearing for the driver bar. At its upper end said bar is connected by short links 195 to a cam lever 196 provided with short trunnions 197 turning in bearings at the top of frame 2. Powerful coiled springs 198 are 55 each connected at one end to a trunnion 197

and at the other end to a plug or block 199 which may be rotated in a split sleeve 198 supported in the machine frame and clamped in desired position by screws 199' engaging recesses in the sleeve. By rotatably adjusting the plugs 199 the tension of springs 198 may be varied, thus regulating the force exerted upon the lever 196 and hence the force with which a fastening is driven. 75

On the lower side of lever 196 are two lugs 200 between which is mounted a cam roll 201 which rests upon the edge cam 202 fixed on the main shaft 5. 70

The driver bar is provided at its upper end with a fixed collar or shoulder 203 which comes into engagement with a stop or cushion 204 shown as a series of washers of leather or like material into or through which the bushing 194 extends. Preferably, these washers are contained in an exteriorly threaded cup 205 which may be rotated in a correspondingly threaded socket 206 in the upper end of the swinging head 101 for the purpose of raising the stop to 90 compensate for wear of the washers. It will be noted that, by adjusting the stop in this manner, the stroke of the driver bar and the force exerted by the springs in driving the fastenings is made substantially constant. 95 A clamping stud 207 may be provided to hold the cup in adjusted position. 100

By reason of the elasticity of the stop 204, the driver bar tends to rebound from it after its driving stroke. The outline of cam 100 202 is such that it will pick up or act to raise the driver bar during a period when it is rebounding from the work and before it starts downward again after such a rebound. It will be noted that the cam roll 105 swings in the arc of a circle about the axis of the trunnion 197 of lever 196. In the position shown in Fig. 5, the roll 201 is just about to leave the high part of the cam at the point *a* and the driver bar and driver are 110 just about to start downward on the driving stroke. The roll leaves the periphery of the cam immediately after it passes point *a*. The driver and driver bar descend under the influence of springs 198 until collar 203 115 strikes the stop 204 and then immediately rebound. The roll after leaving the cam near point *a* does not come again into contact with it until it reaches approximately the point *b*, which occurs during the first 120 upward or rebounding stroke of the driver bar after the fastening has been driven and, therefore, the cam acts to raise or pick up the bar as the driver rebounds from the work. The shape of the cam surface from 125 the point where the roll 201 leaves it to the point where the roll again engages it is shown as complementary to the circular path of the roll relatively to the moving cam surface, but with a slight clearance, so that the 130

roll will not strike the cam surface during, or at the end of, the driving stroke. Fixed in the swinging head 101, also, is the wire cutter 210 which coöperates with the stationary cutting edge 162 of block 161 to sever a partially-formed fastening from the wire and shape its point in substantially the same manner as was fully described in the patents above mentioned. By a rotation of pivot shaft 102, the position of the swinging head 101 may be varied so as to adjust the height of cutter 210 relatively to the stationary cutting edge 162.

The swinging head 101 is oscillated backwardly and forwardly to put the awl and the driver alternately in operative position or in approximate alinement with the tip of work-support 30, to sever the partially-formed fastening, to carry said fastening to anvil 163 where its formation is completed, and finally to put it into alinement with the passage 211 in the foot 93 through which the fastening is driven into the work. For oscillating the head 101, a link 212, pivoted in ears 213 at the rear side of the head, is connected to a lever 214 swinging on the eccentric portion of the pivot shaft 59 adjustably secured in the frame. At its upper end, lever 214 is provided with a cam roll or stud 216 running in cam track 217 on the right side of cam block 21, as seen on Fig. 4. By turning the pivot shaft 59 in the frame, the location of the swinging head at the ends of its to-and-fro movement may be adjusted to bring the awl, driver, and former into proper position to coöperate with the blocks 160, 161 and the presser-foot 93.

After the proper length of wire has been fed through the groove between blocks 160 and 161, as above described, the forward end of block 160 is sprung toward block 161 to clamp the wire while the shaper 171 is giving it the first bend to define the distance of the head of the fastening from the point of the shank and while the cutter 210 is coöperating with the fixed cutting edge 162 of block 161 to sever and point the shank. For this purpose, a slight recess 218 is made near the rear side of block 160 in which rests the forward end of a strut 219, the rear end of which is in position to engage the end of an adjusting screw 220, extending from the rear, partly through a tapped hole 221 in a lug 222 which projects downwardly from the hub of lever 61. To prevent the strut 219 from falling out of place, its front end is maintained constantly in the recess 218 by a light spring 223 bearing against the front side of lug 222 and against a shoulder 224 on the strut, the strength of the spring being insufficient to force blocks 160 and 161 together to clamp the wire. When the arm 61 is oscillated to raise the work-support, as above described, the rear end of strut 219 is sustained in tapped hole 221,

but not until near the end of the rearward movement of the arm and after the feeding of the wire is completed does the end of screw 220 engage the strut 219. Thereafter, during the last portion of this movement of arm 61, the block 160 is sprung toward block 161 so as to clamp the wire. Simultaneously, the work-support 30 is raised slightly farther to compress the work sustained upon it.

When the arm 61 is swung forwardly and the arm 58 is raised after a fastening has been inserted, the work-support is moved downwardly by spring 70 to release the work so that it may be fed the desired distance for the insertion of the next fastening. For feeding the work, a wheel or disk 230 is provided with a roughened or serrated periphery to engage the work. This wheel has also the function of an adjustable gage, as will be described. The hub 231 of this wheel has recesses in its periphery and constitutes one member of a roll clutch similar to that shown in Fig. 8 and already described. The other member 232 of this clutch has a flange 233 which surrounds the hub 231, closing the outer side of the recesses, thus forming tapering or wedge-shaped spaces 234. Springs 235 force the rolls 236 toward the narrow ends of the spaces 234 so that rotation of member 232 in the direction indicated by the arrow in Fig. 7 will cause the rolls 236 to lock the two members of the clutch so that they will rotate together, while rotation of member 232 in the reverse direction will tend to carry the rolls to the wider ends of the spaces 234, so that the backward movement of member 232 will not rotate the work-engaging wheel 230. A spring washer 237 interposed between hub 231 and the supporting bar or slide 238 acts as a brake more certainly to prevent rotation of the work-engaging wheel upon the backward movement of clutch member 232. The wheel 230 rotates loosely upon a headed stud 239 which is screwed into the bar or slide 238 movable toward and from the work in a lever 240. Obviously, however, the usual pawl and ratchet mechanism may be substituted for the roll clutch, if preferred.

The clutch member 232 is oscillated by the same lever 214 that actuates the swinging carrier or head 101, as above described. As shown in Figs. 4 and 6, this lever has a slotted extension or arm 241 in which a block 242 may be fixed in desired position by a headed stud 243 integral with the block and provided with a nut 244 and washer 245, so that the sides of the arm may be clamped between the head of the stud and the washer. A rod 246 is pivotally connected at one end to the stud 243 and at the other to clutch member 232. By changing the position of the block 242 in the slot in

- arm 241, the distance between successive fastenings in the work may be varied. Since the feed wheel 230 has the function also of a gage, provision is made for adjusting it to and from the work and for locking it in adjusted position. The bar 238 is cut away on one side for about half of its width to receive a clutch block 250 which is adjustably connected to the bar by a thumb screw 251, 5 a spring 251' being interposed between the bar and block to take up any backlash. The clutch block 250 is also cut away on one side and has two oppositely inclined surfaces 255. A clutching roll 256 is interposed between each of the inclined surfaces and the adjacent wall 257 of the slot or opening in lever 240 and is normally forced by a spring 258 into the narrower end of the tapering space formed between said surface and wall. 10 The block 250, the bar 238, and the wheel 230 are thus locked in any position to which they may be moved. Each of the clutching rolls 256 may be moved toward the wider end of the tapering space in which it lies, 15 when it is desired to adjust the gage, by one of two pins 259 slidable in block 250 and in position to be engaged by one end of a lever 260 pivoted upon an extension 261 of lever 240. The end of lever 260 passes 20 through a slot 262 in the side of the enlarged end of lever 240 in which the bar 238 and clutch block 250 slide and extends into a pocket in the block between the adjacent ends of pins 259. When lever 260 is moved 25 in either direction its end first engages one of the pins 259 and releases the corresponding clutching roll 256, as described, and then, as it is moved farther, the end engages the side wall of the pocket in which it lies 30 and carries with it the block 250, and therefore the gage wheel 230. When the movement of the lever is stopped the released clutching roll 256 is again moved by its spring 258 into locking position and the 35 gage is then held firmly in its new position.
- In this class of machines, it is often desirable to move the gage quickly to any one of two or three predetermined positions, thereby varying correspondingly the distance from the edge of the work at which the fastenings will be inserted. To this end, the lever 260, as shown in Fig. 6, has on one arm a projection 263 provided with a recess 264. This projection is held by a spring 265 in engagement with a cam surface 266 of a T-shaped lever 267 pivoted on the extension 261 of lever 240. As illustrated, this cam surface is made up of two outwardly-inclined surfaces 268, which meet 40 in an edge adapted to rest in the recess 264. When the lever 267 is in this central position the gage or feed wheel 230 is in its forward position, so that the fastenings will be inserted nearest the edge of the work. 45 If the operator wishes to retract the gage,
- he moves lever 267 from its central position. The coöperation of the projection 263 with one of the surfaces 268 permits lever 260 to be moved by its spring 265. This movement is limited by the engagement of one of two adjustable stop screws 269 in the head of lever 267 with a fixed stop 270 on extension 261. If the two inclined surfaces, the two coöperating sides of projection 263, and the adjustment of the two screws 269, are 50 all respectively alike, as shown in Fig. 6, then the gage will be retracted substantially the same distance when lever 267 is moved to both extreme positions. However, the stop screws 269 may be adjusted to vary the positions that the gage will take when the lever 267 is moved in either direction laterally from its central position, thus giving three predetermined positions to which the gage may be quickly and readily moved. 55 Moreover, as above described, the gage may be independently adjusted by rotation of thumb screw 251. The lever 240 is supported so that the gage may be adjusted vertically. For this purpose, the rear end 60 of the lever is provided with a "three point bearing." The lever has two similar feet 274, one of which is shown in Fig. 4. The toe 275 of each foot bears directly against a part of the machine frame while through 65 the web 276, which connects the feet, passes an adjusting screw 277 bearing against another part of the frame. A screw 278, which passes somewhat loosely through the frame and a retaining plate 52 and aids in clamping 70 it in place, is threaded into each foot, serving to clamp the foot of the lever firmly to the frame. Hence the height of the gage may be regulated by loosening screws 278, if necessary, adjusting screw 277 and then tightening up screw 278. 75
- The work gage just described is not herein specifically claimed since it forms the subject-matter of another application filed by this applicant May 21, 1907, Serial No. 110 374,852.
- As above explained the machine always stops at approximately the same point in its cycle of operations. When the machine is at rest, the horn-actuating arm 58 is 80 raised so that the horn or work-support 30 is in its lowest position, the swinging head 101 is at or near the end of its backward movement, the awl, the driver and the former are raised, and the pivoted carrier 85 115 76 is in an intermediate position with the cutting device 75 above the plane of the lower face of the presser-foot and the closing device 89 retracted so as to be out of alignment with the vertical passage through 120 the presser-foot.
- To start the machine, the treadle 16 is depressed, turning shaft 13 to retract brake shoes 22 from the peripheries of cam blocks 21 and 21^a and withdrawing finger 11 from 125

engagement with slidable pin 10 to cause the clutch members to be engaged. As soon as the main shaft commences to rotate, the work-support 30 is raised, at first yieldingly 5 through spring 57 and then positively as the pawls 65 engage the ratchet teeth 66 on the slide 51. Meanwhile the wire-feeding mechanism has been drawn backwardly so that it now moves forwardly to feed the 10 wire through the groove between blocks 160 and 161 a distance controlled by the position of the block 144 in the slotted arm 145, which position is determined, as above described, by the thickness of the work 15 clamped between the work-support 30 and the presser-foot 93. While the wire is being fed, the pivoted carrier 76 is moved to cause the cutting device 75 to make the 20 opening in the surface of the stock for the head of the fastening. Then, the awl 100 is brought down to make the hole for the shank of the fastening. Just after the feeding of the wire is completed, block 160 is forced toward block 161 to clamp the 25 wire. The former 170 now moves downwardly from the position of Fig. 11 to that of Fig. 12, the shaper 171 giving the first bend to the wire. The swinging head 101 next moves forwardly, the cutter 210 severing 30 the partially-formed fastening from the wire clamped between the blocks 160 and 161.

The forward movement of the swinging head 101 continues until the former and the 35 cutter have pushed the fastening into position over the anvil 163, whereupon the former descends and the bender 172 acts upon the short end of the wire to form the head of the fastening with a depending 40 point which, preferably, extends at a small acute angle to the shank. At or near the end of the downward movement of the former, the swinging head again moves forwardly sufficiently to push the fastening off 45 the anvil. By reason of the tendency of the depending point to spring away from the shank, the fastening is held frictionally in the guideway or driver passage 173 till driven out by the driver. Since the same 50 cam track 217 that oscillates the swinging head also actuates the driving member 232 of the roll clutch which forms a part of the mechanism for feeding the work, this member 232 is retracted in the direction opposite 55 to that indicated by the arrow in Fig. 7 at the same time that the swinging head moves forwardly, as just described. The driving member 134 of the wire-feeding mechanism is also retracted in the direction opposite to 60 that indicated by the arrow in Fig. 8 during the forward movement of the swinging head. This movement of the wire-feeding mechanism is made in two parts or steps, the first 65 of which is that just referred to. At the end of this first movement, the slot in arm 145 is

left substantially vertical so that, when the machine is at rest, vertical movements of the work-support will not cause the wire to be fed forwardly. The second part or step of the backward movement of the wire-feeding mechanism takes place just after the machine starts or substantially at the beginning of the cycle of operations, as stated above.

Soon after the fastening is pushed off the 75 anvil the driver 192 descends, driving the fastening into the openings made for it in the work, the point of the shank being clenched or turned backwardly into the work, as shown in Figs. 15 and 18. As the driver 80 rebounds from the work, its lifting mechanism picks it up and raises it to its highest position as already described. Just after the driver starts upwardly, the closing device 89 is actuated to force down the lips *m* of the 85 stock previously raised by the cutting device 75, so as to close the opening and cover the head of the fastening. While the closing device is operating, the former 170 is raised and as soon as the opening has been closed, 90 the work-support 30 starts downwardly slowly, the former 170 begins to move backwardly and simultaneously the feeding of the work by wheel 230 begins. If the treadle 16 is still depressed, the machine will continue to repeat the cycle of operations, above described, indefinitely. In the continuous 95 operation of the machine at usual speeds, the work-support moves downwardly so slowly that, when released by its lifting mechanism, it can descend only a short distance before it is raised again by that mechanism to clamp the work. If the treadle is released the machine will come to a stop just before, or at the end of, the movement of wheel 230 for 100 feeding the work forward, the work-support taking its lowest position so that the work 105 may be removed.

Although the present invention has been herein described as embodied in one specific machine, it is obvious that in its broadest aspects the invention is not limited to the details of construction nor to the particular mode of operation illustrated and described but that the various features of the invention may be used separately or in combination in machines specifically different in construction and operation, but within the scope 110 of the invention as defined in the claims.

Having described my invention, what I 115 claim as new and desire to secure by Letters Patent of the United States, is:—

1. In a machine of the class described, a plurality of separately operable devices for forming in stock an opening for the head and shank of a fastening, and means for driving the fastening into said opening.
2. In a machine of the class described, means for forming an opening for the head of a fastening, means for forming another

opening for its shank, separate mechanisms for actuating said means, and means for inserting a fastening into said openings.

3. In a machine of the class described, means for forming an opening in the stock for the head of a fastening and for forming another opening for its shank, means for inserting a fastening into said openings, and means for closing the stock over the fastening.

10 4. In a machine of the class described, means for forming an opening in the stock for the head of a fastening, independent means for forming another opening for its shank, means for inserting a fastening into said openings, and means for closing the stock over the fastening.

15 5. In a machine of the class described, means for forming an opening for the shank of a fastening in stock having a recess in its surface to receive the head of the fastening, means for inserting the fastening, and means for closing the stock over the fastening.

20 6. In a machine of the class described, stock-feeding mechanism, means for forming in the stock an opening for the head of a fastening, means for forming another opening for its shank, means for inserting a fastening into said openings, and means for closing the stock over the fastening, each of said means operating to perform its function between successive operations of the stock-feeding mechanism.

25 7. In a machine of the class described, means for forming a recess in the surface of the stock to receive the head of a fastening, means for forming in the stock a hole extending from said recess to receive the shank of the fastening, means for inserting the fastening, and means for closing the stock over the fastening.

30 8. In a machine of the class described, a movable device for forming in the stock an opening to receive the head of a fastening, in combination with an awl and a driver movable alternately into the path of movement of the said device, and means for actuating said parts.

35 9. In a machine of the class described, a device movable in the direction in which the work is fed for forming a comparatively shallow recess to receive the head of a fastening, a carrier movable transversely to the direction of feed, an awl bar and a driver bar movable in the carrier, an awl secured to the awl bar for forming in the work a hole extending from said recess to receive the shank of the fastening, a driver secured to the driver bar for inserting the fastening, a device for closing the stock over the fastening, and means for actuating said parts.

40 10. A machine for securing together layers of material by means of fastenings each having both of its ends hook-shaped to engage different layers of material with a single

strand of wire connecting said ends, comprising means to form from continuous wire a fastening having a shank and a hook-shaped head, means for forming at each operation a single opening through the stock to receive the shank of the fastening, means to drive the fastening so that its shank will enter said opening and its hook-shaped head will enter the material, and means to turn back or 70 clench the point of the shank, thus forming 75 a hook to engage the stock.

11. In a machine of the class described, a vertically movable work-support, a vertically movable awl bar having an awl, a lever having connections to the work-support and to the awl bar and provided with a stud and a cam engaging said stud to actuate the awl bar and the awl for penetrating the work, said connections and said stud being proportioned and arranged to insure that a movement of the work-support shall cause a corresponding movement of the awl whereby the awl in its lowest position is at a predetermined distance from the work-support whatever the thickness of the work.

90 12. In a machine of the class described, a vertically movable work-support, a lever connected to said work-support, a vertically movable awl bar having an awl, a second lever connected to said awl bar and provided with a stud and with a connection to the first lever, and a cam having a groove in its side to receive and sustain said stud, whereby a movement of the work-support causes the second lever to swing upon its stud as a fulcrum so as to produce an equal movement of the awl, while the cam is adapted to produce an independent movement of the awl relatively to the work-support for penetrating the work.

100 13. In a machine of the class described, a vertically movable work-support, a lever connected to said work support, a vertically movable awl bar having an awl, a second lever connected to said awl bar, means, including an adjustable pivot for connecting said levers, the parts being so arranged that the awl in its lowest position will be at a predetermined distance from the work support whatever the thickness of the work, and means for moving the awl bar relatively to the work-support to cause the awl to enter the work.

110 14. In a machine of the class described, a vertically movable work-support, a vertically movable awl bar having an awl operating with the work-support, connections between said work-support and said awl bar proportioned and arranged to insure that the awl in its lowest position shall be at a predetermined distance from the work-support whatever the thickness of the work, said connections including an adjustable eccentric pivot whereby the said distance may be varied, and means for moving 120 125 130

the awl bar relatively to the work-support to cause the awl to enter the work.

15. In a machine of the class described, mechanism for forming a fastening from continuous wire, means for feeding the wire to said mechanism, and means operated automatically to vary the length of wire fed by changing the rate of feed without changing substantially the points in the cycle of operations at which the feed begins and 10 ends.

16. In a machine of the class described, mechanism for forming a fastening from continuous wire, means for feeding the wire to said mechanism, and means controlled automatically by the work for accelerating or retarding the rate at which the wire is fed to vary the length of wire fed according to the thickness of the work, whereby the 20 time during which the feed is taking place is substantially constant with relation to the time occupied by the whole cycle of operations of the machine.

17. In a machine of the class described, mechanism for forming a fastening from continuous wire, means for feeding the wire to said mechanism comprising a wire-engaging device and means for actuating said device including an arm or crank having an adjustable connecting pin, and means operated automatically whenever any change occurs in the thickness of the work for adjusting the position of the connecting pin and thereby varying the length of wire fed 30 to form a fastening.

18. In a machine of the class described, a work-support, mechanism for forming a fastening from continuous wire and for inserting it into work sustained on said work-support, means for feeding the wire to said mechanism comprising a wire-engaging device and means for actuating said device including a slotted arm or crank and a block movable in the slot to vary the length of the 40 wire fed, and connections between the work-support and the block to cause them to move in unison whereby the length of the fastening is determined by the thickness of the work upon the work-support.

50. 19. In a machine of the class described, a vertically movable work-support, mechanism for forming a fastening from continuous wire and for inserting it into work sustained on said work-support, a wire-engaging device, a slotted arm or crank, a block movable in the slot, connections from said block to the wire-engaging device, connections between the work-support and the block to cause them to move substantially 55 vertically in unison; whereby the length of the fastening is determined by the thickness of the work upon the work-support, and means for actuating said arm or crank to feed the wire to the forming mechanism and 60 to leave the slot of the arm or crank approxi-

mately vertical when the machine is at rest so that movement of the work-support at that time will not actuate the wire-engaging device.

20. In a machine of the class described, 70 a shaft, means operated automatically to caliper work of variable thickness, mechanism for forming from continuous wire a fastening having a shank and a hook-shaped head and for inserting said fastening into 75 the work, means for feeding the wire to said mechanism comprising a wire-engaging device and connections therefrom to said shaft which include a slotted arm or crank and a block slideable in the slot toward and from 80 the axis of the arm or crank, and positive connections from the caliper means to the block whereby the length of wire fed is varied, said parts being constructed and arranged so that the shank of the fastening 85 shall have a length determined by the thickness of the work but the length of the head of the fastening will not be varied.

21. In a machine of the class described, a shaft, means operated automatically to 90 caliper work of variable thickness, mechanism for forming from continuous wire a fastening and for inserting said fastening into the work, means for feeding wire to said mechanism comprising a wire-engaging 95 device and connections therefrom to said shaft which include a slotted arm or crank and a block slideable in the slot toward and from the axis of the arm or crank, and positive connections from the caliper means 100 to the block whereby the length of the wire fed is varied so that the length of the fastening is determined by the thickness of the work, the parts being so constructed and arranged that when the machine is at rest any movement of the caliper means at that 105 time will not actuate the wire engaging device.

22. In a machine of the class described, mechanism for forming a fastening from 110 continuous wire, means for feeding the wire to said mechanism comprising a wire engaging device, a clutch, and mechanism including a reciprocating member for actuating said device in one direction only through 115 said clutch, and means controlled by the thickness of the work for automatically varying the length of the wire fed by changing the rate of movement of said member without changing substantially the points in 120 the cycle of operations at which such movement begins and ends.

23. In a machine of the class described, mechanism for forming a fastening from 125 continuous wire, means for feeding the wire to said mechanism comprising a wire-engaging device, a roll clutch, mechanism including a reciprocating member connected to said clutch to operate said device, and means for adjusting the movement of said member 130

- automatically but without changing substantially the points in the cycle of operations at which such movement begins and ends to vary the length of wire fed according to the thickness of the work. 5
24. In a machine of the class described, means operated automatically to caliper work of variable thickness, mechanism for forming from continuous wire a fastening 10 having a shank and a hook-shaped head, means controlled by said caliper means for varying the length of the shank without varying the length of the head, means for inserting the fastening into the work, and 15 means for feeding the wire after the work has been caliper but before the fastening has been formed and inserted, whereby the length of the shank of a particular fastening is automatically determined by the thickness of the work at the point where said fastening is inserted. 20
25. In a machine of the class described, a driver, a spring-actuated lever connected with the driver and having a cam roll, a cam, 25 means for lifting the lever in opposition to its actuating means and for releasing it to drive a fastening into the work, a stop to limit the movement of the driver, having a surface complementary to the circular path 30 of the roll relatively to the moving cam surface and adapted for returning the driver to normal position as it rebounds from the stop. 30
26. In a machine of the class described, a
- driver, a driver bar, spring-actuated means 35 acting upon said bar to drive a fastening into the work, a stop to limit the downward movement of the bar, a pivoted lever connected to the driver bar, a cam roll carried by said lever, a cam having a surface curved 40 in substantial conformity with the circular path of said roll and terminating in a projection for acting upon said lever to raise the bar as it rebounds from the stop, whereby the force of the rebound is utilized and excessive strain on the lever is avoided. 45
27. In a machine of the class described, a driver, a driver bar, a pivoted lever connected to the driver bar and carrying a cam roll, spring-actuated means acting upon said 50 lever to cause the driver to drive a fastening into the work, and a cam arranged to act upon the lever through said roll and having a portion shaped to release the driver bar and then to raise it as it rebounds from the work, the shape of said portion of the cam being complementary to the circular path of the roll relatively to the moving cam surface, said cam having a slightly recessed portion to provide clearance for said roll. 55

In testimony whereof I have signed my name to this specification in the presence of two subscribing witnesses.

LOUIS A. CASGRAIN.

Witnesses:

FREDERICK L. EDMONDS,
BERNARD BARROWS.

Corrections in Letters Patent No. 1,048,134.

It is hereby certified that in Letters Patent No. 1,048,134, granted December 24, 1912, upon the application of Louis A. Casgrain, of Beverly, Massachusetts, for an improvement in "Machines for Inserting Fasteners," errors appear in the printed specification requiring correction as follows: Page 13, line 25, strike out the word "means"; same page, line 28, before the word "having", insert the words *said cam*; and that the said Letters Patent should be read with these correction therein that the same may conform to the record of the case in the Patent Office.

Signed and sealed this 4th day of February, A. D., 1913.

C. C. BILLINGS,

Acting Commissioner of Patents.

- automatically but without changing substantially the points in the cycle of operations at which such movement begins and ends to vary the length of wire fed according to the thickness of the work. 5
24. In a machine of the class described, means operated automatically to caliper work of variable thickness, mechanism for forming from continuous wire a fastening 10 having a shank and a hook-shaped head, means controlled by said caliper means for varying the length of the shank without varying the length of the head, means for inserting the fastening into the work, and 15 means for feeding the wire after the work has been calipered but before the fastening has been formed and inserted, whereby the length of the shank of a particular fastening is automatically determined by the thickness of the work at the point where said fastening is inserted. 20
25. In a machine of the class described, a driver, a spring-actuated lever connected with the driver and having a cam roll, a cam, 25 means for lifting the lever in opposition to its actuating means and for releasing it to drive a fastening into the work, a stop to limit the movement of the driver, having a surface complementary to the circular path 30 of the roll relatively to the moving cam surface and adapted for returning the driver to normal position as it rebounds from the stop. 30
26. In a machine of the class described, a
- driver, a driver bar, spring-actuated means 35 acting upon said bar to drive a fastening into the work, a stop to limit the downward movement of the bar, a pivoted lever connected to the driver bar, a cam roll carried by said lever, a cam having a surface curved 40 in substantial conformity with the circular path of said roll and terminating in a projection for acting upon said lever to raise the bar as it rebounds from the stop, whereby the force of the rebound is utilized and excessive strain on the lever is avoided. 45
27. In a machine of the class described, a driver, a driver bar, a pivoted lever connected to the driver bar and carrying a cam roll, spring-actuated means acting upon said 50 lever to cause the driver to drive a fastening into the work, and a cam arranged to act upon the lever through said roll and having a portion shaped to release the driver bar and then to raise it as it rebounds from the work, the shape of said portion of the cam being complementary to the circular path of the roll relatively to the moving cam surface, said cam having a slightly recessed portion to provide clearance for said roll. 55
